Assistant Examiner — Lauren McVey(57) **CLAIM**

The ornamental design for a media processing device, as shown and described.

DESCRIPTION

FIG. 1 is a front right perspective view of a media processing device showing our new design;

FIG. 2 is a back left perspective view of thereof;

FIG. 3 is a top view thereof;

FIG. 4 is a bottom view thereof;

FIG. 5 is a left side view thereof;

FIG. 6 is a right side view thereof;

FIG. 7 is a back view thereof; and,

FIG. 8 is a front view thereof.

The dot-dot-dash broken lines immediately adjacent the claim represent the bounds of the claimed design, while all other broken lines are directed to environment and are for illustrative purposes only. The broken lines form no part of the claimed design.

1 Claim, 7 Drawing Sheets(56)
